UNITED STATES PATENT OFFICE.

CONRAD REGENBOGEN, OF KIEL, GERMANY, ASSIGNOR TO FRIED. KRUPP AKTIENGESELLSCHAFT, GERMANIAWERFT, OF KIEL-GAARDEN, GERMANY.

INTERNAL-COMBUSTION ENGINE.

1,152,658.

Specification of Letters Patent. Patented Sept. 7, 1915.

Application filed August 2, 1912. Serial No. 712,905.

To all whom it may concern:

Be it known that I, CONRAD REGENBOGEN, a citizen of the German Empire, residing at Kiel, Germany, have invented certain new and useful Improvements in Internal-Combustion Engines, of which the following is a specification.

It is a common occurrence with internal combustion engines wherein the piston rod runs through the combustion chamber, as for instance in double acting engines, that the piston will be burnt by the influence of the hot gases. The piston rod then becomes rough at the burnt place and will no longer run smoothly in the stuffing box; its strength is generally also affected from the great corrosion caused by the jet of fuel directed against it.

The object of the present invention is now to remove this disadvantage.

In the drawing three embodiments are represented and Figure 1 shows a part of the working cylinder and the piston of an internal combustion engine in longitudinal section; Fig. 2, a similar view to Fig. 1 of a second embodiment of the invention; and Fig. 3 also a similar view to Fig. 1 of a third embodiment of the invention.

Referring first to the embodiment shown in Figs. 1 and 2, A represents the working cylinder of an internal combustion engine, B the piston and C the piston rod, which in the usual manner is attached to the piston head B by means of a cone c' and a nut c^2 . D is the cylinder cover and E the stuffing box.

The combustion chamber F is pocket shaped and is as usual situated in the projecting part of the cylinder cover.

Valves, necessary for controlling the working of an engine of this kind, are situated in the valve borings G, which open into the combustion chamber as indicated in the drawing.

In accordance with this invention, the piston head, see Fig. 1, is provided with an annular rib H which is adapted to register with a corresponding groove H' in the cylinder cover when the piston head is nearing its dead center position, that is at the instant when the temperature in the combustion chamber is highest; or as shown in the modified form of Fig. 2, an annular rib D ^{2} is provided on the cylinder cover and a corresponding groove or recess B ^{2} in the piston

head for the same purpose. The hot gases remaining in the combustion chamber F can therefore not directly reach the piston rod, but they now instead come in contact with the annular rib H, whereby an effective protection of the piston rod against burning is obtained.

The protection of the piston rod C ^{3} in the modified form of the invention shown in Fig. 3, is attained by providing a sleeve K, made of fire proof material, around the piston rod at the endangered place, which sleeve may moreover be effectively cooled in the manner indicated by the arrows in the drawing.

I claim:

1. In an internal combustion engine having a piston rod running through the combustion chamber, means for completely covering the piston rod thus protecting it from direct contact with the combustion gases at the instant when the temperature is highest in the combustion chamber, said means comprising interengaging male and female members.

2. In an internal combustion engine, the combination of a housing, a combustion chamber, cylinder cover, and piston having the piston rod running through said chamber, with an annular male member and a corresponding female member, adapted to register with each other thus completely inclosing said piston rod at the instant of the highest temperature in the combustion chamber, whereby said piston rod will be protected from direct contact with the hot gases.

3. In an internal combustion engine, the combination of a housing, a combustion chamber, cylinder cover, and piston having the piston rod running through said chamber; with an annular male member and a corresponding female member, adapted to register with each other thus completely inclosing said piston rod at the instant of the highest temperature in the combustion chamber, whereby said piston rod will be protected from direct contact with the hot gases; said members situated one on said piston and the other on said cylinder cover.

4. In an internal combustion engine having a cylinder, cylinder cover, piston and piston rod running through the combustion chamber, means for completely covering the piston rod thus protecting it from direct

2
contact with the combustion gases at the instant when the temperature is highest in the combustion chamber; said means comprising an annular rib on said piston and a corresponding groove in said cylinder cover.

5. In an internal combustion engine having a piston rod running through the combustion chamber, means for completely covering the piston rod and protecting it from direct contact with the combustion gases at the instant when the temperature is highest in the combustion chamber; said means comprising an annular male member partaking of the movement of said piston and a corresponding stationary female member adapted to register with the male member at the instant of the highest temperature of the combustion gases.

10. In an internal combustion engine having a piston rod running through the combustion chamber, means for completely covering the piston rod and protecting it from direct contact with the combustion gases at the instant when the temperature is highest in the combustion chamber; said piston rod

being provided with a longitudinal passage for a flow of cooling fluid, and ports leading from said passage directed so as to admit the cooling fluid to said means.

15. In an internal combustion engine having a piston rod running through the combustion chamber, means for completely covering the piston rod and protecting it from direct contact with the combustion gases at the instant when the temperature is highest in the combustion chamber; said means comprising an annular male member attached to the piston rod and a corresponding stationary female member adapted to register with the male member at the instant of explosion; said piston rod being provided with a longitudinal passage having branches for directing cooling fluid against said male member.

20. In testimony whereof I have affixed my signature in presence of two witnesses.

CONRAD REGENBOGEN.
